RESILIENT DRIVING MECHANISM

Frank L. Alben, Pittsburgh, Pa., assignor to Westinghouse Electric Corporation, East Pittsburgh, Pa., a corporation of Pennsylvania

Application June 10, 1943, Serial No. 490,311

5 Claims. (Cl. 64—27)

My invention relates, generally, to resilient driving mechanisms and, more particularly, to mechanisms suitable for driving locomotives having a relatively large horsepower.

The utilization of a steam turbine for driving a locomotive results in a saving in fuel and water and at the same time increases the horsepower output without exceeding the present rail weight limits. At the present time, turbine-driven locomotives are being designed which will develop from 5 to 10 thousand horsepower and will operate at speeds up to 120 M. P. H. A locomotive of this type requires a resilient drive capable of transmitting more horsepower than the maximum capacity of drives previously available.

An object of my invention, generally stated, is to provide a resilient driving mechanism which shall be simple and efficient in operation and which may be economically manufactured and installed.

A more specific object of my invention is to provide a resilient driving mechanism which shall be capable of transmitting a relatively large amount of power.

Another object of my invention is to provide a resilient driving mechanism having a relatively large amount of torsional flexibility.

A further object of my invention is to provide a resilient driving mechanism which permits a relatively large amount of misalignment between the driving and driven elements of the mechanism.

Still another object of my invention is to provide a resilient driving mechanism which can be mounted directly on the axle of a locomotive or other vehicle.

Other objects of my invention will be explained fully hereinafter or will be apparent to those skilled in the art.

In accordance with my invention, the spider of a multi-spring cup drive is mounted directly on an axle of a locomotive and the spring cups are removably disposed in a gear rim center which surrounds the axle and encloses the hub of the spider. The gear rim center is rotatably mounted in a gear casing which encloses the entire drive. Sufficient clearance is provided between the gear rim center and the axle to permit misalignment of the axle, thereby functioning in a manner similar to a quill drive.

For a fuller understanding of the nature and scope of my invention, reference may be had to the following detailed description, taken in conjunction with the accompanying drawings, in which:

Figure 1 is a view partially in section and partially in elevation of a resilient drive embodying my invention, the section being taken along the line I—I of Fig. 2; and

5 Fig. 2 is a view, partially in elevation and partially in section, taken along the line II—II of Fig. 1.

Referring to the drawings, locomotive wheels 10 are secured to an axle 11 which is driven by 10 a resilient driving mechanism comprising a spider hub 12 secured to the axle 11 and having a plurality of radially extending arms 13, and a gear rim center 14 which surrounds the axle 11 and is spaced therefrom. The gear rim center 14 is provided with a hollow central portion for receiving the spider hub 12 and has a plurality of radially extending brackets 15 which are disposed between the arms 13 of the spider hub 12. A cover plate 16 is removably attached to the gear rim center 14 by means of a plurality of stud bolts 17.

The gear rim center 14 is rotatably mounted on bearings 18 disposed in bearing housings 19 which, in turn, are removably secured in a gear case 21 by means of a plurality of tap bolts 22. The gear case 21 encloses the entire driving mechanism, thereby affording a means of properly lubricating the mechanism and excluding dirt therefrom.

In order to transmit torque resiliently between the gear rim center 14 and the spider hub 12, a 30 plurality of helical springs 23 is disposed in each one of the brackets 15 to engage a pair of arms 13 on the spider hub 12. As shown more clearly in Fig. 2, each one of the springs 23 is retained in position by two cup-like members 24 which are 35 provided with flanges 25 at their inner edges. Shouldered retaining bushings 26 are provided for slidably supporting the spring cups 24 and are so disposed within the bracket 15 as to prevent the spring cups from being forced out of the bracket. The cups 24 and the bushings 26 are 40 retained in the bracket by caps 27 which are removably secured to the bracket by a plurality of bolts 28 and 29.

A gear rim 31, having a plurality of teeth 32 45 thereon, is removably secured to the gear rim center 14 by means of the caps 27 and the bolts 29. As shown, the bolts 29 are so disposed on the dividing line between the brackets 15 on the gear rim center 14 and the gear rim 31 that they function 50 as keys to prevent the gear rim from turning on the gear rim center.

As shown in Fig. 2, the bottoms of the cups 24 are forced outwardly by the spring 23 against the arms 13 of the spider hub. The arms 13 are provided 55 with wearing plates 33 which abut the bot-

toms of the cups 24. In this manner, torque may be transmitted in either direction between the gear rim center and the spider hub which, as explained hereinbefore, is secured to the axle 11. The gear rim center may be driven by a suitable pinion (not shown) which engages the teeth 32 of the gear rim 31.

Referring to Fig. 1, it will be seen that, in view of the clearance provided between the gear rim center 14 and the axle 11, a predetermined amount of misalignment between the driving and the driven elements of the mechanism may take place without interfering with the operation of the driving mechanism. Thus, if one wheel should pass over a low spot in the track, thereby causing one end of the axle 11 to drop, the driving mechanism continues to function in its normal manner. In this manner a quill, usually provided in similar drives, is not required, thereby materially simplifying the present structure as compared with previously known drives.

Furthermore, the space required for the driving mechanism is materially reduced since the spider hub is disposed inside of the gear rim center and not alongside of the center, as in previous structures. As explained hereinbefore, the present driving mechanism may be readily enclosed by a gear case, which is an additional advantage of the present structure. In view of the compactness of the present mechanism, it may be mounted on a locomotive axle between journal bearings 34, thereby making it suitable for turbine-driven locomotives wherein the driving gears are located inside of the locomotive frame. The oil seals 35, herein illustrated, form no part of the present invention and are fully described and claimed in a copending application.

From the foregoing description, it is apparent that I have provided a resilient driving mechanism which is capable of transmitting a relatively large amount of power and which requires a relatively small amount of space. Furthermore, the present mechanism may be mounted directly on the axle of a locomotive or other vehicle and permits a relatively large amount of misalignment of the axle without interfering with the operation of the mechanism or causing excessive wear on the parts of the mechanism.

Since numerous changes may be made in the above described construction and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. In a resilient driving mechanism, in combination, a rotatable shaft, a hub secured to the shaft, said hub having a plurality of radially extending arms, a gear rim center surrounding the shaft and enclosing said hub, a cover removably secured to one side of the gear rim center, said gear rim center having a plurality of circumferentially disposed radially outwardly extending brackets disposed between the arms on said hub, a resilient member disposed in each of said brackets outside of said cover for engaging said arms, a gear rim removably attached to said brackets,

and means for rotatably supporting said gear rim center.

2. In a resilient driving mechanism, in combination, a rotatable shaft, a hub secured to the shaft, said hub having a plurality of radially extending arms, a gear rim center surrounding the shaft and enclosing said hub, a cover removably secured to one side of the gear rim center, said gear rim center having a plurality of circumferentially disposed radially outwardly extending brackets disposed between the arms on said hub, a resilient member disposed in each of said brackets outside of said cover for engaging said arms, a gear rim removably attached to said brackets, and a gear case for rotatably supporting said gear rim center, said gear case enclosing said gear hub and said gear rim center and said gear rim.
3. In a resilient driving mechanism, in combination, a rotatable shaft, a hub secured to the shaft, said hub having a plurality of radially extending arms, a gear rim center surrounding the shaft and spaced therefrom, said gear rim center having a plurality of radially extending brackets disposed between the arms on said hub, a plurality of resilient members disposed in each of said brackets for engaging said arms, cup means slidably disposed in said brackets for individually retaining said resilient members in said brackets, a gear rim removably attached to said brackets, and means for jointly retaining said cup means and said gear rim in position.
4. In a resilient driving mechanism, in combination, a rotatable shaft, a gear rim center surrounding the shaft and spaced therefrom, said gear rim center having a hollow center portion and a plurality of brackets extending radially therefrom, a hub secured to the shaft and disposed in the hollow portion of the gear rim center, said hub having a plurality of radially extending arms disposed between the brackets on the gear rim center, a plurality of resilient members removably disposed in each of said brackets for engaging said arms, cup members slidably disposed in said brackets for retaining said resilient members in said brackets, a gear rim removably attached to said brackets, and means for jointly retaining said cup members and said gear rim in position.
5. In a resilient driving mechanism, in combination, a rotatable shaft, a gear rim center surrounding the shaft and spaced therefrom, said gear rim center having a hollow center portion and a plurality of brackets extending radially therefrom, a hub secured to the shaft and disposed in the hollow portion of the gear rim center, a cover removably secured to one side of the gear rim center to enclose the gear hub, said hub having a plurality of radially extending arms disposed between the brackets on the gear rim center, a plurality of resilient members removably disposed in each of said brackets for engaging said arms, cup members slidably disposed in said brackets for retaining said resilient members in said brackets, a gear rim removably attached to said brackets, and means for jointly retaining said cup members and said gear rim in position.

FRANK L. ALBEN.
